UNITED STATES PATENT OFFICE.

LOUIS A. LEU, OF FESSENDEN, NORTH DAKOTA.

CIGAR-HOLDER..

No. 895,568.

Specification of Letters Patent.

Patented Aug. 11, 1908.

Application filed March 21, 1908. Serial No. 422,476.

To all whom it may concern:

Be it known that I, LOUIS A. LEU, a citizen of the United States, residing at Fessenden, North Dakota, have invented certain new and useful Improvements in Cigar-Holders, of which the following is a specification.

This invention relates to improvements in cigar holders.

The object of this invention is to provide a holder that will obviate clipping the end of the cigar, which operation, as is well known, usually produces an unraveling of the outer leaf covering.

Another object of this invention is to maintain the cigar, while being smoked, in a perfectly fresh condition and at the same time prevent fouling of the smoke.

Still another object contemplated by this invention is the provision of means for effectually eliminating a quantity of nicotin and tobacco tar from the smoke before the latter has reached the mouth of the smoker.

To the accomplishment of the recited objects and others coördinate therewith, the preferred embodiment of the invention resides in that construction and arrangement of parts hereinafter described, illustrated in the accompanying drawings and embraced within the scope of the appended claims.

In said drawings: Figure 1 is a side elevation of the complete holder, showing the cigar in dotted lines, and Fig. 2 is a longitudinal section taken along lines $x-x$ thereof. Fig. 3 is a detail perspective view of the slideable band. Fig. 4 is a longitudinal section showing the adaptation of an ordinary cigar holder to the nicotin trap. Fig. 5 is a detail fragmentary section of one of the terminals of the smoke tubes.

Similar numerals of reference indicate corresponding parts throughout the several views.

The detachable mouth-piece preferably of amber and designated in the drawings by numeral 1, is provided with a metal tube 2, open at both ends and disposed at an inclination, each terminal being screw-threaded and engaging respectively, with the complementary screw-threaded metal grip 3 and the annular flange 4 of the nicotin trap 5, against which the terminal of the amber mouth-piece abuts and forms a perfectly tight and even joint. This tube serves not only to reinforce the amber mouth-piece but should the latter become broken or otherwise impaired, resort could be had to the auxiliary tube. The fact

that the tube and mouth-piece could be curved and still retain the same coöperative features is another advantage of this organization.

The hollow cylindrical nicotin trap formed of metal, hard-rubber or any other suitable material, has its forward end slightly reinforced, as at 6. Located diagonally opposite the annular flange 4 is a screw-threaded opening 7, so that in case there was a failure to remove the screw-plug 8 at the bottom of the trap, quite a large quantity of foreign matter could accumulate before an overflow occurred at the opening 4. This feature of the invention is considered to be a marked improvement over devices of a similar nature, as it may be used interchangeably with a pipe or cigar holder of the common type. Fig. 4 discloses this interchangeable feature as applied to a cigar holder 18.

The holder intended to be utilized in connection with the nicotin trap comprises a pair of spring steel tubes 9, having angularly bent hollow piercing pins 10, beveled as represented in Fig. 5 of the drawings, and arranged diametrically opposite each other to conform to the shape of a cigar and terminating at a common outlet 11, which is in communication with the nicotin trap. The screw-threaded extension 12, the curved flange 13 and the smoke tubes are formed integrally with one another.

In order to secure the cigar in proper position there is provided a circular slideable band 14, with oppositely disposed eyelets 15 for engagement with the smoke tubes. As the cigar is consumed to a point adjacent the piercing pins the band 14 is manipulated forward to release said pins and then backward to hold the cigar in its readjusted position. Thus it will be observed that by the use of the smoke tubes the smoke is not drawn through the whole length of the cigar but only through sections or portions thereof and the remainder of the cigar is kept fresh until the very end. In contradistinction to gripping the cigar on opposite sides thereof, as hereinbefore set forth, hollow tubes or darts may be employed and the same result attained by forcing the latter into the end or side of the cigar and adjusting it gradually as the cigar is being consumed.

The legs 16 on the nicotin trap are used when the ordinary type of holder is applied, and those on the band, designated by reference numeral 17, when the tubular holder

is utilized, the function in each case being to elevate the cigar a sufficient distance from the surface of furniture or the like and thereby prevent burning of the latter.

5 It is evident that the smoke tubes, single hollow tubes or darts and reinforced mouth piece, in fact, all of the various parts of this invention, could be used in conjunction with the ordinary type of holder.

10 This invention is simple in construction, comparatively cheap to manufacture, neat in design and the component parts thereof can be segregated and re-assembled with facility.

15 It should be understood that in its broader aspects the invention comprehends the employment not only of the various means described, but of equivalent means for performing the recited functions.

20 While the arrangement shown is thought, at the present time, to be preferable, it is desired to reserve the right to effect such modifications and variations thereof as may come fairly within the scope of the appended claims.

25 Having thus described the invention, what is claimed, is:

1. The combination with a cigar holder, of a main mouth-piece, an auxiliary mouth-piece, and an intermediate nicotin trap, said auxiliary mouth-piece being inclosed by said main mouth-piece and thereby constituting a core for the latter.

2. The combination with a cigar holder, of a main mouth-piece, an auxiliary mouth-piece, an intermediate nicotin trap, said auxiliary mouth-piece being inclosed by said main mouth-piece, both of said mouth-pieces being detachably connected to each other and the nicotin trap, and a removable grip carried by the auxiliary mouth-piece for holding the main mouth-piece in proper relative position.

3. The combination with a cigar holder comprising a pair of yieldable smoke tubes, of main and auxiliary mouth-pieces, an intermediate nicotin trap, and means carried by said tubes for securing and releasing the cigar.

4. The combination with a cigar holder comprising a pair of diametrically disposed yieldable smoke tubes adapted to fit closely

against opposite sides of the cigar, main and auxiliary mouth-pieces, an intermediate nicotin trap, and means carried by said tubes for securing and releasing the cigar. 55

5. The combination with a cigar holder comprising a pair of diametrically disposed yieldable smoke tubes adapted to fit closely against opposite sides of the cigar, main and auxiliary mouth-pieces, an intermediate 60 nicotin trap, and a band carried by and adapted to slide over said tubes, thereby causing the tubes to contract or expand with respect to the cigar.

6. The combination with a cigar holder 65 comprising a pair of integrally formed diametrically disposed yieldable smoke tubes adapted to fit closely against opposite sides of the cigar, main and auxiliary mouth-pieces, an intermediate nicotin trap, and a band carried by and adapted to slide over said tubes, thereby causing the tubes to contract or expand with respect to the cigar.

7. The combination with a cigar holder comprising a pair of integrally formed dia- 75 metrically disposed yieldable smoke tubes provided with piercing terminals and adapted to conform to the shape of a cigar and fit closely against opposite sides thereof, main and auxiliary mouth-pieces, an intermediate 80 nicotin trap, and a band carried by and adapted to slide over said tubes, thereby causing the tubes to contract or expand and respectively, engage or disengage the cigar.

8. The combination with a cigar holder, of 85 main and auxiliary mouth-pieces, an intermediate nicotin trap having an inlet and an outlet, said inlet being below the outlet, a clean-out plug for said trap, said main mouth-piece having an inclined bore adapted 90 to receive said auxiliary mouth-piece and communicate with said outlet, the auxiliary mouth-piece having a removable grip for securing the mouth-pieces in proper relative position to each other and the nicotin trap. 95

In testimony whereof I have hereunto set my hand in presence of two subscribing witnesses.

LOUIS A. LEU.
